UNITED STATES PATENT OFFICE.

OREN K. BOYETT, OF DOUCETTE, TEXAS.

MATCH BOX.

1,412,671.

Specification of Letters Patent. Patented Apr. 11, 1922.

Application filed June 25, 1920. Serial No. 391,682.

To all whom it may concern:

Be it known that I, OREN K. BOYETT, a citizen of the United States, residing at Doucette, in the county of Tyler and State 5 of Texas, have invented certain new and useful Improvements in Match Boxes, of which the following is a specification.

The object of the present invention is to provide an improved form of match box capable of being easily repaired and formed of parts few in number and removably associated so as to be readily taken apart.

An additional object is to provide an improved form of match box comprising a 10 supporting frame of a light skeleton structure designed for the insertion therein of wire gauze material suitable to complete the article into a receptacle or holder for matches.

With the above and other objects in view, the invention may be said to reside generally in the details of construction, combination and arrangement of parts as will be hereinafter more fully pointed out, reference being had to the accompanying drawings wherein.

Figure 1 is a front elevation of a match box constructed in accordance with the invention.

Figure 2 is a vertical longitudinal section taken on the line 2—2 of Figure 1 and

Figure 3 is a horizontal cross section taken on the line 3—3 of Figure 1.

In carrying out the objects and purposes 35 of the invention, the improved match box is formed primarily of a skeleton frame 1 and a wire gauze body forming material 2 supported by and attached to the frame.

The main frame consists of an elongated narrow strip of sheet metal folded lengthwise

40 to provide a U-shaped channel extending throughout its length. The channeled strip is then bent to provide side portions 3 and 4 to extend oppositely from each other in

45 spaced parallel relation from the bowed or intermediate portion 5, thus forming a U-shaped or horse shoe frame substantially as illustrated with the channeled portions of the strips facing inwardly, and providing a

50 slot or guide way for the material 2 when the latter is inserted into the frame from the opened end. The frame is pierced at intervals with transversely extending openings

55 to which tightening bolts 6 are passed to draw the slot forming walls of the frame toward one another so as to firmly clamp

the wire gauze material inserted therebetween. The fasteners are removable so that they can be readily loosened to permit removal of the member 2 whenever required. 60

Projecting outwardly from one side of the frame at a point remote from its lower or opened edge is a receptacle forming upper member 7 folded longitudinally to provide a channeled member substantially in the 65 same manner as in the case of the frame. The member 7 is however, bowed to form a semi-circular band with its terminal ends respectively secured by welding or otherwise, to the frame at directly opposite points on 70 the side members 3 and 4 thereof as shown to advantage in Figures 1 and 3 of the drawing. It is to be noted that the member 7 is fastened to the outermost of the slot forming walls of the same and consequently 75 interferes in no way with the insertion or removal of the wire gauze member of backing 2. Directly below the member 7 is a second lower semi-circular member comprising an inner band 8 and an outer embracing 80 clamp 9. The ends of the band are likewise secured to the side strips of the frame and on the same side as the member 7, projecting laterally from adjacent the lower edge of the frame to provide in common 85 with the upper member reinforcements for supporting the frame work of the match holding receptacle. Both upper and lower members are provided with a plurality of 90 openings for the reception of bolts 10. These 95 bolts may be provided with enlarged fanciful heads if desired so as to add to the attractiveness and completeness of the match holder.

The inner structure of the match holder is 95 formed of a strip of wire gauze or mesh such as indicated at 2 and inserted into the frame from the lower end, being received in the channel or slotted portions of the frame. The strip 2 is, of course, cut to conform to 100 the shape of the frame so that it will snugly engage both the top section 5 as well as the side strips 3 and 4 and is positively clamped in place and held against slipping or working loose upon tightening of the bolts 6. 105 The lower portion of the strip extending beyond the frame at its lower end is adapted to be employed to form a bottom for the match receptacle and is extended beneath band 8 as shown with its edges turned upwardly upon the outside of the band against 110 which it is clamped so that upon tighten-

ing the bolts of the lower member it will be clamped between the band 8 and the clamp 9. An auxiliary strip 12 is then employed to form the side walls of the match receptacle, 5 being secured between the upper and lower members so as to provide an enclosed space open only at the upper end and adapted to conveniently hold a liberal supply of matches. This auxiliary strip is fastened 10 along its upper edge to the slotted portion of the member 7 and firmly clamped upon tightening of the fasteners 10 while its lower edge is clamped between the band 8 and the clamp member 9 jointly with the edges of 15 the bottom strip 11. The strip 12 of the match receptacle and 2 of the holder frame may, if preferred, be formed of a single piece of material, the strip being made integral with the bottom section 8 by way of 20 forming separate lateral extensions capable of being bent upwardly to provide continuous side walls for the match receptacle, or in any other suitable manner.

To strengthen the holder adjacent the receptacle bearing end, a pair of inner and outer cross strips or braces 13 and 14 respectively are provided and extend transversely of the frame from one side strip of the frame to the other, immediately adjacent the point where the members 7 and 8 are secured to the frame. These cross braces tend to reinforce the frame and to provide stiffening elements to prevent it from becoming distorted or unshapely at the end 35 where it is most subject to handling. Riveted to the cross piece 5 and at a suitable place is a hanger or strap 15 having an enlarged perforated head 16 designed for insertion over a nail or other supporting object where- 40 by the holder may be hung upon a wall or other support. This match holder may be hung at any appropriate and convenient place and provides a most convenient and handy receptacle for matches. The matches 45 are to be deposited in the receptacle at the lower end of the holder and will at all times remain dry and available for instant use owing to the porous character of the receptacle and the fact that it is of an openwork 50 character. The length of the frame or back 1 provides an appropriate striking surface, the igniting of the matches occurring as the head thereof is scratched upon the roughened surface provided by the wire gauze 2. 55 The wire gauze, therefore, not only provides a frame work for the holder but in addition thereto forms a friction surface on which

to rub and ignite the matches. Being of a light and open work character, the holder may be readily and conveniently handled 60 and at the same time any necessity for replenishing the supply of matches in the receptacle can at once be seen as the latter are clearly visible through the wall 12. The removable fasteners permit the frame and 65 inner material to be easily and readily taken apart and separated whenever desired either to repair or to substitute a new striking surface or to remedy any defects in the match receptacle. From the foregoing it may be 70 obvious that various changes in regard to the construction, arrangement of parts and details of construction may be resorted to as fall within the scope of the appended claims and consequently it is to be understood that the same is not limited to the precise details herein described or illustrated but that such changes may be resorted to as properly fall within the scope of the invention set forth in the accompanying claim. 80

Having thus described my invention what I claim as new and desire to secure by Letters Patent is:—

A match receptacle of the class described comprising an inverted U-shaped main frame made of suitable sheet metal folded to provide a U-shaped channel with its channel portions facing inwardly, said main frame having suitable bolt openings, an upper semi-circular channel frame member having its opposing ends fixed to said main frame, a lower semi-circular outer clamping band, a lower inner semi-circular clamping band, a wire gauze strip inserted into said channeled main frame member the lower end 90 thereof projecting outward and clamped between said lower semi-circular members, all of said frame members having suitable bolt openings, an auxiliary strip of wire gauze forming a receptacle clamped in said channel frame member at its upper end and between said lower semi-circular clamping bands, bolts in said openings to draw said members together for holding said gauze members, and a pair of outer transverse 95 cross strips held adjacent to the lower ends of said frame members, all as and for the purpose set forth.

In testimony whereof I affix my signature in presence of two witnesses.

OREN K. BOYETT.
